(57) **CLAIM**

The ornamental design for a display device, as shown and described.

DESCRIPTION

FIG. 1 is a left side view of a display device showing our new design;

FIG. 2 is a right side view of the display device of FIG. 1; FIG. 3 is a front view of the display device of FIG. 1, the broken-lines being illustrative of the environment and forming no part of the claimed design;

FIG. 4 is a rear view of the display device of FIG. 1;

FIG. 5 is a top plan view of the display device of FIG. 1, the broken-lines being illustrative of the environment and forming no part of the claimed design;

FIG. 6 is a bottom view of the display device of FIG. 3; FIG. 7 is a front view of the display device of FIG. 1 as seen along line A of FIG. 1, the broken-lines being illustrative of the environment and forming no part of the claimed design; and,

FIG. 8 is a front view of the display device of FIG. 1 as seen along line B of FIG. 1, the broken-lines being illustrative of the environment and forming no part of the claimed design.
